UNITED STATES PATENT OFFICE.

PETER W. SPRECHER, OF MILWAUKEE, WISCONSIN.

ELECTRIC-LIGHTING FIXTURE.

1,154,070.

Specification of Letters Patent. Patented Sept. 21, 1915.

Application filed May 15, 1915. Serial No. 23,305.

To all whom it may concern:

Be it known that I, PETER W. SPRECHER, a citizen of the United States, and resident of Milwaukee, in the county of Milwaukee and State of Wisconsin, have invented certain new and useful Improvements in Electric-Lighting Fixtures; and I do hereby declare that the following is a full, clear, and exact description thereof.

10 My invention consists in what is herein particularly set forth with reference to the accompanying drawings and pointed out in the claims of this specification, its object being to facilitate the insulation and hanging 15 of electric-lighting fixtures by simple, economical and efficient means.

Figure 1 of the drawings represents a partly sectional elevation of insulating means in accordance with my invention applied in connection with the canopy of an electric-light fixture and an attaching screw, which screw is shown in engagement with a support in a ceiling, and Fig. 2, represents a horizontal section on the plane indicated by line 2—2 in Fig. 1.

Referring by numerals to the drawings, 3 indicates a ceiling or wall box into which a conduit 4 for electric-current distribution wires 5 and 6 extends. Screw threaded 20 on a nipple 7 in the box is a cap 8 engaged by a suspending screw 9 for a block 10 preferably of indurated fiber or other suitable insulating material that is shouldered to have fit in a canopy 11 such as is common 25 with electric-light fixtures. The insulating-block is partly counterbored to provide for the seating therein of a sleeve 12 of indurated fiber or other suitable insulating material through which the suspending screw 30 9 extends, and said block is provided with opposite longitudinal passages for the wires 5 and 6 aforesaid. The insulating-block is also provided with opposite lateral recesses 35 with which pivot-branches 13 of a hanger-link 14 of an electric-light fixture engage. 40 However it is within the scope of my invention as herein claimed to otherwise

adapt said block for the connection therewith of an electric-light fixture, according to the demands of the trade.

50 The block and sleeve aforesaid combine to form an insulating fixture-loop by which to do away with the usual insulating joint with a ceiling or wall connection, and an insulating ring on the canopy. It is also 55 to be noted that the block of my insulating loop has two wire passages instead of one, and that said loop is centrally fastened to a support by a single screw central thereof.

The block 10 may be of other than insulating material when used on lathe and plaster work, brass, for instance, being suitable for the purpose. The sleeve 12 therewith is always of insulating material.

I claim:

1. An electric-lighting fixture-loop comprising a canopy fitting centrally counterbored block of insulating material through which to extend an attaching-screw and provided with passages for current distribution wires, together with a screw insulating sleeve seated in the counterbore of said block.

2. An electric-lighting fixture-loop comprising a canopy-fitting block of insulating material having a central bore through which to extend an attaching-screw, passages for current distribution wires and recesses for pivot-ends of a hanger; and a screw-insulating sleeve extending from the block.

3. An electric-lighting fixture-loop comprising a centrally counterbored canopy fitting block through which to extend an attaching-screw and provided with passages for current distribution wires, together with a screw-insulating sleeve seated in the counterbore of said block.

In testimony that I claim the foregoing I have hereunto set my hand at Milwaukee 90 in the county of Milwaukee and State of Wisconsin.

PETER W. SPRECHER.
